UNITED STATES PATENT OFFICE.

JOHN HANCOCK, OF PHILADELPHIA, PENNSYLVANIA.

WIRES FABRIC.

1,272,660.

Specification of Letters Patent. Patented July 16, 1918.

Continuation in part of application Serial No. 186,092, filed August 14, 1917. This application filed April 3, 1918. Serial No. 226,415.

To all whom it may concern:

Be it known that I, JOHN HANCOCK, a citizen of the United States, residing at Philadelphia, county of Philadelphia, and 5 State of Pennsylvania, have invented a certain new and useful Wire Fabric, of which the following is a specification.

The present application is filed as a continuation in part of application filed August 14, 1917, Serial No. 186,092, and relates to wire fabric for use in connection with spring mattresses. Some of the objects of this invention are to provide a fabric formed of a plurality of interconnected units which 10 are so constructed and arranged as to form a flat even surface to support a mattress or the like; to provide a fabric of elastic nature which will not sag or stretch out of shape in use; to provide a fabric the units 15 of which are each formed of a plurality of loops one formed as a continuation of the other; and to provide a fabric with interlocked removable units wherein a unit section can be readily disconnected for repair 20 or replacement.

In the accompanying drawing—

Figure 1 represents a plan of a portion of a fabric embodying this invention; Fig. 2 represents a section on line 2—2 of Fig. 1; 25 and Fig. 3 represents a portion of one of the unit sections.

Referring to the drawings a portion of the fabric supporting frame is shown in the transverse angle bar 10 and side bar 11 to 30 the former of which the fabric is attached by the usual springs 12. It will be understood that the frame is of the customary rectangular form with the fabric suspended between the transverse angle bars while these 35 latter are braced by the side bars.

The fabric of the present invention is formed of a plurality of unit sections 13, each section consisting of a wire bent to 40 form a number of large loops 14 lying in the same plane and having sides 15 of equal length which converge toward the open part of the loop where each is reversely bent and merges into the next adjacent reversely bent portion of the side of the next large loop. 45 Thus the main loop wire continues from one large loop to the next in the form of double hooks 16 and 17 connected by a well-rounded bridge part 18. The sides 15 of two adjacent loops 14 are spaced relatively close together so that the length of a unit section

is made up of alternate wide and narrow loop parts, the former being connected by a bridge piece 20, and the latter by the double-hook bridge piece 18. Each end of the bridge piece 20 is joined to the respective 50 sides 15 of the unit loop by substantially U-shaped offsets 19, which are located entirely within the complete length of the transverse connecting bridge piece 20, so that the sides 15 are left straight throughout their length in 55 order to resist tensional strain without stretching. Furthermore the provision of the offsets 19 prevents lateral spreading of the section loops in assembled condition, since each offset 19 forms a seat to receive one of the hook 60 parts 16 or 17 and when these hook parts are engaged, as shown in Fig. 1, the edges of the respective offsets abut the wire of the hook at each side and anchor the connected parts against lateral relative movement. The 65 bridge pieces 20 are preferably all in alignment in the respective sections to form uniformly spaced transverse supports for the 70 mattress or other device.

The ends 21 of the wire forming each unit 75 section are respectively reversely bent and arranged to lie in the same plane as the section loops but relatively close to the last loop and substantially parallel to the side frame bars 11 thus not only giving a finished 80 selvage but reinforcing the structure. In order to retain these ends 21 fixed as an operative part of the fabric, a hook 22 is formed by bending the wire in the desired 85 manner and in the same direction as the 90 bend of the double hooks 16 and 17.

To assemble the unit sections, one section is placed partially over another and the several double hook loops of the upper section inserted between and pushed through the 95 respective openings between the sides 15 of adjacent large loops. The lower section is then moved in a direction to bring its double hooks 16 and 17 into hooked relation with the offsets 19 of two adjacent large loop 100 bridge pieces 20, thus interconnecting the two sections and since the hook 16 engages one offset 19 and the hook 17 the next adjacent offset 19, a straight line tension is 105 maintained through the aligned hooks and 105 loop sides. In addition the bridge piece 18 between the double hooks prevents lateral spreading or opening up of the different loops which action is further prevented by the seating of the hooks in the offsets 19. 110

In the assembled condition, it will be noted that the hooks 16 and 17 are all disposed on the bottom of the fabric thereby providing an upper supporting surface free from 5 hooks, joints or sharp ends which in the ordinary fabric are destructive to the mattress or catch in and tear the bed covering.

Any suitable means may be employed for 10 securing the fabric to the springs of the main frame, and in the present instance a transverse rod 23 having looped ends is inserted within the hooks of the end unit sections and to these rods the springs 12 are secured in a well-known manner.

15 It will now be apparent that I have devised a novel and useful construction which embodies the features of advantage enumerated as desirable in the statement of the invention and the above description; and 20 while I have in the present instance shown and described the preferred embodiment thereof which has been found in practice to give satisfactory and reliable results, it is to be understood that the same is susceptible 25 of modification in various particulars without departing from the spirit or scope of the invention or sacrificing any of its advantages.

What I claim is:

30 1. A metal fabric for mattresses comprising a plurality of elongated unit sections, each section consisting of a unitary structure forming wide loops at one edge and hooks at the opposite edge, said loops and 35 hooks alternating throughout the length of the section, the sides of adjacent pairs of

wide loops diverging toward and merging into said hooks and the opposite ends of said sides being in close proximity, said hooks each being adapted to interengage with a 40 pair of wide loops at the point of close proximity, whereby all of said sections are united to form a complete fabric.

2. A metal fabric for mattresses comprising a plurality of elongated unit sections, 45 each section consisting of a unitary structure forming a plurality of wide loops at one edge and double hooks at the opposite edge, said wide loops respectively having transverse bridge pieces provided with pairs 50 of offsets located entirely within the length of said bridge pieces, said hooks being each adapted to interengage with a pair of offsets whereby all of said sections are united and lateral spreading prevented.

55 3. A metal fabric for mattresses comprising a plurality of relatively long narrow unit sections, each section consisting of a unitary structure bent to form a plurality 60 of loops located side by side, hooks respectively interconnecting adjacent parts of said loops, a bridge piece for each loop forming with the loop sides offsets projecting toward the next section, said hooks each interengaging with an offset of one loop and an 65 offset of the abutting loop, whereby in assembled condition said sections are united and lateral displacement of the hook parts prevented.

In testimony whereof I have hereunto 70 signed my name.

JOHN HANCOCK.
